UNITED STATES PATENT OFFICE.

WILLIAM OWEN, OF PITTSBURGH, PENNSYLVANIA, ASSIGNOR TO PITTSBURGH PLATE
GLASS COMPANY, A CORPORATION OF PENNSYLVANIA.

PLATE-GLASS-POLISHING APPARATUS.

Application filed June 5, 1923. Serial No. 643,540.

To all whom it may concern:

Be it known that I, WILLIAM OWEN, a citizen of the United States, and a resident of Pittsburgh, in the county of Allegheny and State of Pennsylvania, have made a new and useful invention in Improvements in Plate-Glass-Polishing Apparatus, of which the following is a specification.

The invention relates to apparatus for polishing plate glass. It is designed particularly for that type of apparatus in which the glass to be polished is carried beneath a series of polishers on cars or other carrier apparatus, but is not limited to use in such connection as it is of utility when used in connection with the ordinary polishing machine having a rotating polishing bed or table which carries the glass. After a certain period of use, the felts of the runners become caked with rouge or other polishing material and their efficiency is reduced. The principal object of the invention is to provide a simple, convenient arrangement whereby the polishing blocks may be removed for the purpose of cleaning the felts or renewing them without raising the runner frame, and to accomplish this result with a minimum expenditure of time and effort. Certain embodiments of the invention are illustrated in the accompanying drawings wherein:

Figure 1 is a side elevation of the complete apparatus. Fig. 2 is a partial plan view of the runner frame construction at the edge thereof. Fig. 3 is a section on the line III—III of Fig. 2. Fig. 4 is a view similar to that of Fig. 2 illustrating a modification. Fig. 5 is a section on the line V—V of Fig. 4. Fig. 6 is a sectional view illustrating another modification. And Fig. 7 is a section on an enlarged scale on the line VII—VII of Fig. 6.

Referring to the general arrangement of parts as shown in Fig. 1, the reference numeral 1 designates the framework of the machine; 2 is a supporting bracket carried by the framework; 3 is a car mounted upon the track 4 and carrying the glass to be polished; 5 is a rack carried upon the bottom of the cars and driven from the shaft 6 through the gears 7 and 8; 9 is a tubular support provided at its upper and lower ends with bearings in which is journaled the runner shaft 10; 11 is an electric motor which drives the shaft 10 through the inter-

mediary of gearing located in the casing 12; 13 is the runner frame secured to the lower end of the runner shaft and carrying the blocks or runners 14; 15 is a lever provided with a hooked end as indicated at 16 and engaging trunnions 17 carried by the gear casing 12; 18 is a link pivoted to the bracket 2 and provided with hook shaped ends 19 engaging trunnions 20 carried by the tubular support 9; 21 is a rod connected to the lever 15 for raising and lowering the runner, such rod being threaded as indicated at 22 and passing through the bracket 23; and 24 is a hand wheel threaded onto the rod whereby it may be raised and lowered.

The polishing block 14 is provided with the usual felt 25 and spindle 26 projecting up through the bearing member 27 carried by the runner frame 13. The bearing member is provided with a shank 28 projecting into the frame member 13 as indicated in Fig. 3 and provided with an angular recess 29. A set screw 30 set at an inclined position as indicated in Fig. 3 engages the wall of the recess 29 and serves to maintain the bearing member 27 securely in position. When it is desired to remove the runners for cleaning or repair, the runner which is to be removed is brought next to the side of the car as indicated in Fig. 3 and the set screw 30 is loosened, permitting withdrawal of the bearing member 27 and the runner carried thereby. The runner may be cleaned by means of washing and scraping and then replaced, or a spare runner may be substituted. The other runners may be removed and handled in the same manner. It will be noted that the runners may be removed and replaced without lifting the runner frame 13, although, if desired, such runner frame might be lifted so as to make all of the runners clear the glass, the cotter pins 31 being engaged by the tops of the bearing members at such time, after which the procedure of removing and handling the runners is the same as heretofore described.

Figs. 4 and 5 illustrate a modification which permits the same general method of procedure. In this construction the runner frame 13^a is provided with sockets 32 receiving the bearings 33, which in turn receive the spindles 26 of the runners 14. The bearings are held against vertical movement by means of the set screws 34. The sockets 32 are provided with laterally extending open-

ings or slots 35 of a width just sufficient to permit the passage therethrough laterally of the spindles 26. When it is desired to remove one of the runners, the set screw 34 is screwed back to release the bearings 33, and such bearing is moved vertically until it clears the top of the frame 13^a, after which the runner can be removed laterally, the spindle 26 passing through the slot 35.

10 As in the other construction, the spindle is provided with a cotter pin 31.

Figs. 6 and 7 illustrate another method of securing the lateral removal of the runners without moving the runner frame vertically so as to clear the runner spindle and without removing the cotter pin at the upper end of such spindle. In this construction, the runner 14^a is provided with a perforated lug 35 which fits inside of a hollow spindle 36, 20 such spindle passing up through the runner frame 13^b and being provided with a cotter pin 31 as in the other type of construction. The lug 35 is secured to the spindle 36 by means of a bolt 37 provided 25 with a cotter 38. When it is desired to remove the runner, the bolt 37 is removed and the spindle 36 raised, which frees the lug 35, so that the runner can be removed laterally for replacement or cleaning.

30 What I claim is:

1. In apparatus for polishing plate glass, a rotatable runner frame, a carrier for the glass mounted for movement beneath said

frame, and a plurality of polishing blocks or runners releasably mounted on the frame 35 for free rotation about their vertical axes, and removable laterally from said frame without lifting said frame from operative position.

2. In apparatus for polishing plate glass, 40 a rotatable runner frame, a carrier for the glass mounted for movement beneath said frame, and a plurality of polishing blocks having vertical spindles extending upward through said frame, and securing means 45 whereby the blocks may be removed horizontally from the frame when it is in operative position upon releasing said securing means.

3. In apparatus for polishing plate glass, 50 a rotatable runner frame, having a plurality of vertical sockets opening laterally, bearings seated in said sockets, means for rotating said frame, a carrier for the glass mounted for movement beneath said frame, 55 and a plurality of polishing blocks or runners having vertical spindles extending upward through said bearings, the said spindles being of such diameter that they may be removed through the lateral openings 60 from the sockets after the bearings are removed from said sockets.

In testimony whereof, I have hereunto subscribed my name this 26th day of May, 1923.

WILLIAM OWEN.
